CLAIM

The ornamental design for a poultry spreader tool, substantially as shown and described.

DESCRIPTION

FIG. 1 is a left side elevational view of a poultry spreader tool showing my new design, the right side being a mirror image thereof;

FIG. 2 is front elevational view thereof;

FIG. 3 is a rear elevational view thereof;

FIG. 4 is a top plan view thereof;

FIG. 5 is a bottom plan view thereof; and

FIG. 6 is a perspective view thereof.

FIG. 1

FIG. 2

FIG. 3

FIG. 4

FIG. 5

FIG. 6
